UNITED STATES PATENT OFFICE.

SAMUEL KURILOFF, OF NEW YORK, N. Y., ASSIGNOR TO LEHMAN BROTHERS SILVER-WARE CORPORATION, OF NEW YORK, N. Y., A CORPORATION OF NEW YORK.

DESIGN FOR A BEVERAGE URN OR SIMILAR ARTICLE.

Application filed December 21, 1926. Serial No. 20,105. Term of patent 3½ years.

To all whom it may concern:

Be it known that I, SAMUEL KURILOFF, a citizen of the United States, residing in New York, New York, have invented a new, original, and ornamental Design for Beverage Urn or Similar Article, of which the following is a specification, reference being had to the accompanying drawing, forming part thereof.

I claim:

The ornamental design for a beverage urn or similar article, as shown.

SAMUEL KURILOFF.
